UNITED STATES PATENT OFFICE.

JOHN JOSEPH O'BRIEN, OF BROOKLYN, NEW YORK.

CHECK-PROTECTOR.

1,389,377.

Specification of Letters Patent. Patented Aug. 30, 1921.

Application filed June 1, 1921. Serial No. 474,193.

To all whom it may concern:

Be it known that I, JOHN J. O'BRIEN, a citizen of the United States, and resident of the city of New York, borough of Brooklyn, 5 in the county of Kings and State of New York, have invented a new and Improved Check-Protector, of which the following is a full, clear, and exact description.

My invention relates to a check protector, 10 and aims to provide new and useful improvements in connection with a device of this character.

It is a well appreciated fact that any number of devices have been placed upon the 15 market by means of which the body of a check or similar instrument might be marked to preclude any danger of its amount being raised or the written matter upon the same being otherwise altered.

20 These devices have further offered objections in that primarily they could not be placed upon the market at a nominal figure, and secondly that the mechanism necessary presented such a cumbersome aggregate as 25 to make it impossible for a person to carry the same.

With these objects in mind my present invention aims to provide a check protector which will primarily be of such a simple 30 construction as to permit of its being placed upon the market at a nominal figure.

A further object of my invention is the 35 construction of a device of the character stated which shall be extremely light and compact so that it may at all times be carried in the pocket, and so as to be instantly available upon a check or similar paper being written.

With these and other objects in mind reference is had to the attached sheet of drawings which latter illustrate practical embodiments of the same and in which;

Figure 1 is a side view of my protector and showing the same in association with a 45 fountain pen.

Fig. 2 is a fragmentary enlarged sectional view thereof, and

Fig. 3 is a side view of a protector embodying my construction.

50 It will be seen in Figs. 1 and 2 that the reference numeral 5 indicates the cap portion of a fountain pen or other writing implement, while the reference numeral 6 in Fig. 3 indicates the handle of any desired 55 construction or material, my improved check protector hereinafter described being applied

to these members, it being understood that these elements form no part of my invention and that the protector is capable of association with any desired base which may 60 constitute any convenient part of an implement.

Referring now more particularly to Fig. 2 it will be seen that the reference numeral 7 indicates a cap which constitutes a housing for the protector, this cap being slidably retained in this mounting by utilizing a pin 8 secured to this mounting which extends through the slot 9 forming a part of the cap 7 it being also noted in this connection 70 that the cap 7 is normally retained projected preferably by means of a spring 10 interposed between the end of the base and the inner end of the cap 7.

Further it will be seen that a pair of lugs 75 11 form continuations of the base portion, and are inclosed within the cap 7, and between these lugs a toothed wheel 12 is rotatably mounted, the outer edge of the wheel being in line with a slot 13 formed in the 80 apex of the cap 7.

Thus reference being had to Fig. 1 it will be seen, assuming that a check has been written and that the writing on the same is to be protected against alteration, an operator may reverse the pen utilized so that the cap 7 is pressed into intimate engagement with the surface of the check 14. Upon this occurring the cap 7 will be pressed inwardly 90 against the tension exerted by the spring 10, and the teeth of the wheel 12 will extend through a slot 13 and beyond the cap 7 so that the same bear against the surface of the check 14 whereby upon the entire mounting carrying the cap 7 being slid across the 95 surface of writing a series of indentations or perforations will be formed, obviously precluding the alteration of the writing thereon due to the fact that any erasure of this writing would immediately become apparent.

Reference being had to Fig. 3 it will be noted that the operation and construction of the parts is identical with that disclosed in Figs. 1 and 2 with the exception that a different form of mounting is utilized, but it will 105 be appreciated that any desired member may constitute the mounting for the cap 7 and that my invention resides in the protector proper, the parts of the latter being obviously desirable to alteration without in the 110 least departing from the scope of my claims, which are:

1. A protector including a means presenting a mounting, a cap slidably secured to said mounting and means within said cap and projectable beyond the same for permitting of the forming of indentations upon a piece of paper.
2. A check protector including means providing a cap slidably secured to said mounting, said cap being formed with a slot in its apex, and a toothed wheel rotatably secured to said mounting and in line with the slot in said cap.
3. A check protector including means providing a cap slidably secured to said mounting, said cap being formed with a slot in its apex and means for normally projecting said cap, a toothed wheel rotatably secured to said mounting, and in line with the slot in said cap.
4. A check protector including means providing a mounting, a cap formed with a slot, a pin secured to said mounting and ex-

tending through said slot, a spring interposed between the end of said mounting and the inner face of said cap for normally projecting the latter, said cap being formed with a slot in its apex portion, and a toothed wheel rotatably secured to said mounting and in line with the slot in said cap.

5. A check protector including means providing a mounting, a cap formed with a slot, a pin secured to said mounting and extending through said slot, a spring interposed between the end of said mounting and the inner face of said cap for normally projecting the latter, said cap being formed with a slot in its apex portion, a pair of lugs secured to and forming a continuation of said mounting, a toothed wheel rotatably secured within said lugs whereby upon said cap being retracted the teeth of said wheel will project through the slot in the apex of said cap.

JOHN JOSEPH O'BRIEN.
